COMBINED SPLICING TAPE DISPENSER AND RECORDING TAPE SPLICING BLOCK

Charles L. Alden, White Bear Lake, Minn., assignor to Minnesota Mining and Manufacturing Company, St. Paul, Minn.

Filed Sept. 9, 1971, Ser. No. 179,257

Term of patent 14 years

Int. Cl. D16—05

U.S. Cl. D61—1 Q

FIG. 1

FIG. 4

FIG. 5

FIG. 2

FIG. 6

FIG. 3

FIG. 7

FIG. 1 is a perspective view of a combined splicing tape dispenser and recording tape splicing block showing the front side, top and left end of my new design;

FIG. 2 is a front elevation thereof;

FIG. 3 is a top plan view thereof;

FIG. 4 is a left end view thereof rotated 90 degrees counterclockwise;

FIG. 5 is a right end view thereof rotated 90 degrees clockwise;

FIG. 6 is a rear elevation thereof;

FIG. 7 is a bottom view thereof; and

FIG. 8 is an exploded perspective thereof rotated 180 degrees as it appears with the front cover removed to show the splicing block on the inner side.

I claim:

The ornamental design for a combined splicing tape dispenser and recording tape splicing block, as shown and described.
